TURNSTILE MECHANISM

Filed Jan. 15, 1930

UNITED STATES PATENT OFFICE

OTTO DISTLER, OF NEW YORK, MAX KLEIN, OF BRONX, AND EUGENE KLEIN, OF NEW YORK, N. Y.

TURNSTILE MECHANISM

Application filed January 15, 1930. Serial No. 420,840.

The main object of this invention is to provide a turnstile as now used in train stations of transport systems which is simple in design and construction and relatively inexpensive in cost.

Another object of the invention is to provide a turnstile for transport systems in which the passenger deposits a coin in the coin box remotely located from the device which energizes a solenoid releasing the turnstile mechanism to permit the passage of the passengers.

Still another object of the invention is to provide a turnstile which is coin released, or whose latching means are coin released upon the depositing of a coin and which may be rotated in one direction but will remain locked when rotated in the opposite direction until such time as a coin is deposited in the mechanism.

The above and other objects will become apparent in the description below in which characters of reference refer to like-named parts in the drawing.

Referring briefly to the drawing, Figure 1 is a top plan view of the turnstile mechanism showing a coin box applied thereto.

Figure 2 is a fragmentary section side elevational view of Figure 1 showing the positioning plungers.

Figure 3 is a longitudinal sectional elevational view taken on line 3-3 of Figure 1.

Figure 4 is a cross sectional view taken on line 4-4 of Figure 3.

Figure 5 is a fragmentary view similar to Figure 3 showing the locking mechanism in closed position.

Referring in detail to the drawing, the numeral 10 indicates a pedestal upon which the turnstile mechanism is mounted. This pedestal is surmounted by a circular cam ridge 11 which is provided with a plurality of arcuately spaced apart cam depressions 12. The turnstile comprises a circular casing 13 having a hub 14 therein which is rotatably secured upon a king-pin 15. The casing is rigidly secured to turnstile arms 15 which are pivotally spaced apart an arcuate distance of 90 degrees so that a pas-

senger may with convenience walk through the enclosure between two of these arms.

For each depression 12 in the cam ring 11 a plunger is provided. These plungers comprise a cylinder 16 which houses a coil spring 17. The coil spring is adapted to yieldably extend a cartridge 18 upon which a hemi-spheroid bolted head 19 is mounted, the head being adapted to ride in and out of the depressions 12 upon the cam ring 11, said plungers being adapted to rotate with the turnstile arms 15.

Within the pedestal in the compartment 20 thereof an electrically operated solenoid is provided with a reciprocating plunger 22 which engages one end of a deformed locking lever 23. The locking lever 23 is pivoted intermediate its length upon a lug 24 and the upper or free end of said lever 25 projects at right-angles to the remainder of the lever 70 and is formed into a hinged end which engages a hinged latching pawl 26. The hinge is so formed that the latching pawl 26 may be freely rotated and tripped when coming in contact with the heads 19 of the plunger as 75 these plungers are rotated and moved with the turnstile arms in a clockwise direction. A coil spring engages a rigid part of the cam spring and is secured to the lever 23 intermediate its length and normally urges said

lever to project said latching pawl into engaging position with the heads of said plungers. A resilient finger 28 is secured to the extension 25 of the swinging lever 23 and its free end engages the latching pawl 26 urging this pawl constantly into extended position. A coin box 29 may be located or mounted at a position remote from the turnstile mechanism and is adapted through mechanical means to close a circuit through the cable 30 to energize the solenoid when a coin has been deposited in member 29 and thus permit the entrance of the passenger upon the station. The turnstile mechanism is adapted to permit the passage of a single 90 passenger into the enclosure when the passenger stations himself between any pair of intersecting arms 15 of the turnstile. The coin is adapted to be deposited in the slot 31 of the coin mechanism. Before this is done, how-

ever, the turnstile is locked from being rotated in a counter-clockwise direction but may be rotated freely and at will in a clockwise direction. This will permit the passengers leaving the station to find ready exit past the turnstile if such passengers will walk between the arms in a clockwise direction. As previously stated, the coin is dropped into the coin box 29 and closes a circuit through means not shown in the drawing and not pertinent to the application, and this circuit being closed energizes a solenoid 21. Previous to this time the latching pawl 26 rises in the path of the passing plunger heads 19 and will not permit the passage of these plungers, thereby locking the turnstile against rotation in a counter-clockwise direction. As soon as the coin is deposited and the solenoid energized the lower end of the lever 23 is pulled toward the solenoid thereby retracting the latching pawl 26 out of super-imposing position over the cam ring 11 and thus permits the passage of members 19. These members 19 are adapted to serve the double purpose of positioning the turnstile so that the arms of the turnstile will always come to rest in the same position and also these members 19 supporting the movable parts of the turnstile between the cam track will tend toward a noiseless performance of the device.

It is to be noted that certain changes in form and construction may be made without departing from the spirit and scope of the invention.

We claim:

1. In a device of the class described, a pedestal, a rotatable turnstile member, plungers projected from said rotatable member, a cam ring mounted on said pedestal, co-operating with said plungers and means on said cam ring for limiting the movement of said rotatable turnstile to 90 degrees and means for locking said plunger against rotation in one direction, depressions in said cam ring of the same number as said plungers to limit the movement of said rotatable turnstile member, a member adapted to project over said cam ring for locking said rotatable member against rotation in one direction and electrically operated means for restricting said member.

2. In a device of the class described, a pedestal, a rotatable turnstile member, plungers projected from said rotatable member, a cam ring mounted on said pedestal co-operating with said plungers, a lever pivoted on said pedestal an electrically operated solenoid for rotating said lever and means on said lever normally projecting across the path of said plunger to lock said plungers against rotation in one direction.

3. In a device of the class described, a pedestal, a rotatable turnstile member, plungers projected from said rotatable member, a cam ring mounted on said pedestal co-operating

with said plungers, a lever pivoted on said pedestal, an electrically operated solenoid for rotating said lever, a latching pawl secured to said lever, said latching pawl being normally projected across the path of said plungers locking said plungers against rotation in one direction.

4. In a device of the class described, a pedestal, a rotatable turnstile member, plungers projected from said rotatable member, a cam ring mounted on said pedestal co-operating with said plungers, a lever pivoted on said pedestal, an electrically operated solenoid for rotating said lever, a latching pawl secured to said lever, said latching pawl being normally projected across the path of said plungers locking said plungers against rotation in one direction, said latching pawl being hingedly connected to said lever, said latching pawl permitting the free passage of said plungers when rotated in one direction, and means for retaining said latching pawl in extended position on said lever.

In testimony whereof we affix our signatures.

OTTO DISTLER.
